MACHINE FOR ASSEMBLING SPOKED WHEELS

Filed March 12, 1928.

UNITED STATES PATENT OFFICE.

WILLIAM N. BOOTH, OF DETROIT, MICHIGAN, ASSIGNOR TO KELSEY-HAYES WHEEL CORPORATION, OF DETROIT, MICHIGAN, A CORPORATION OF NEW YORK.

MACHINE FOR ASSEMBLING SPOKED WHEELS.

Application filed March 12, 1928. Serial No. 261,135.

The invention relates to machines for assembling spoked wheels particularly of that type having wooden spokes and metallic rims. One of the objects of the invention is to so construct the machine that the wheel rims are held circular and to size while the spokes are being assembled therewith so that an inherently balanced spoked wheel may be formed and necessity of machining may be avoided. With these as well as other objects in view, the invention resides in the novel features of construction and combinations and arrangements of parts as more fully hereinafter set forth.

In the drawings:—

Figures 1 and 2 are transverse sections through a machine and wheel embodying my invention and showing the parts of the machine and wheel in different positions;

Figure 3 is a view corresponding to Figure 2 and showing a modified machine;

Figure 4 is a plan view of a portion thereof.

The machine shown in Figures 1 and 2 is designed to assemble a vehicle wheel having the wooden tenoned spokes 1 and the continuous metallic rim 2, which is in the present instance a sheet metal channel-shaped felly. The spokes have double mitered inner ends 3, which in the completed wheel form the hub section. The spokes have at their outer ends the tenons 4 and the annular shoulders 5 surrounding the tenons.

The tenons are engageable in the ferrules 6 upon the base 7 of the felly and extending radially outward from the axis of the wheel, while the annular shoulders are engageable with bosses upon the base and extending radially inward or toward the axis of the wheel. The felly has the front and rear flanges 8 and 9, respectively, which have at their outer edges tapered or flared seats 10 and 11 for engaging a demountable tire carrying rim.

The machine is designed to operate upon the wheels in partially assembled condition where the tenons of the spokes engage the

ferrules 6 of the felly and the inner double mitered ends 3 of the spokes are also partially engaged, the felly being circular and to size. The machine has the base 12 which is provided with the annular flange 13. 14 is an annular ring yieldably supported upon the base by the coil springs 15 and slidably engaging the annular shoulder formed by the flange 13. This annular ring has the lower and upper tapered or flared portions 16 and 16', respectively, at its inner periphery for respectively engaging the seats 10 and 11 upon the felly flanges and holding these seats circular and to size. 17 is an annular ring located concentrically within the ring 14 and guided thereby and yieldably supported upon the base 12 by 65 means of the coil springs 18, the upper face of this ring being engageable with the front side of the front flange 8. 19 is a pressure plate which is vertically movable toward and away from the base and has a downwardly extending or bossed portion 20 adapted to engage the rear side of the rear flange 9 and formed with a tapered or flared outer periphery corresponding to that of the seat 11 to hold this seat against the 70 upper tapered or flared portion 16' of the ring 14 when the felly is in its lowermost position. Downward movement of the pressure plate relative to the ring 14 is limited by means of the annular series of stops 80 21 which are engageable with the upper end of the ring 14. 22 is another pressure plate which is adapted to be moved through the pressure plate 19 and vertically toward or away from the base 12. This pressure plate 85 22 is adapted to cooperate with the pressure plate 23 yieldably supported centrally upon the base 12 by means of the coil springs 24 to force the inner end portions of the spokes into their permanent positions in the plane 90 of the felly. Owing to shape of the inner end portions, the spokes are at this time also forced radially outward to engage their annular shoulders 5 with the bosses upon the base 7 of the felly.

In operation, the partially assembled

wheel is placed in the portion of the apparatus supported upon the base 12 with the front flange 8 lowermost and resting upon the ring 17, the felly engaging pressure plate 19 and the spoke engaging pressure plate 22 at this time being in sufficiently raised position to permit the insertion of the partially assembled wheel. The felly engaging pressure plate is then forced 10 downwardly toward the base 12 by suitable means such as a ram to engage its bossed portion 20 with the rear flange 9 and the tapered or flared seat 11 upon this flange. Upon continued downward movement of 15 this pressure plate it carries the felly downwardly to bring its rim engaging seats 10 and 11 into contact with the tapered or flared portions of the felly truing ring 14, after which this ring 14 and the ring 17 20 are brought into contact with the base. The spoke engaging pressure plate 22 is then forcibly lowered by suitable means such as another ram and cooperates with the pressure plate 23 to angularly move the 25 spokes to their permanent positions in the plane of the felly, the pressure plate 23 at the end of the downward movement of the pressure plate 22 being in contact with the base 12.

30 With this arrangement it will be seen that the felly truing ring 14 with the ring 17 and the pressure plate 19 operate to hold the felly circular and to size and that the ring 17 and pressure plate 19 further operate to hold the front and rear flanges 8 and 9 of the felly in their correct relative positions during lateral forcing of the spokes to their permanent positions. It will also be seen that the inner ends of the spokes 40 are not positively held out against the felly so that all are free to relatively move to distribute the pressure over all and the inner end of a longer spoke may be nearer the axis of the wheel than the others. However, the 45 construction of spokes is such that the annular shoulder of each is forced into firm engagement with the base of the felly. As a result, a wheel assembled in this machine is of the inherently balanced type since the 50 felly is held circular and to size during the assembling operation.

In the modification shown in Figures 3 and 4, a more simple construction is provided in which the felly truing ring 25 and the front flange engaging ring 26 are integral with the base 27, the central portion of which further has the integral pressure plate 28 for engaging the lower sides of the inner end portions of the spokes 29. The rear flange engaging pressure plate 30 is, however, constructed in the same manner as the corresponding pressure plate 29, this also being true of the pressure plate 31 for engaging the upper sides of the inner end portions of the spokes. The spokes 29 instead

of having double mitered inner ends have single miters and are initially assembled with the felly to extend upwardly and inwardly therefrom. The arrangement is such that with the partially assembled wheel inserted in the machine the pressure plate 30 is first lowered to cooperate with the rings 25 and 26 in holding the felly circular and true to size and also holding the front and rear flanges of the felly in their correct 70 relative positions in the same manner as the machine shown in Figures 1 and 2. Then upon lowering the pressure plate 31 the spokes are forced laterally, as well as radially, outward into their permanent positions, 75 at which time their annular shoulders firmly engage the base of the felly.

What I claim as my invention is:

1. In a machine for assembling spoked wheels, the combination with means engageable with the wheel rim to hold the same circular and to size, of means for holding the rim in engagement with said first mentioned means, and means for forcing the spokes into firm engagement with the rim 85 and to their permanent positions while the rim is in engagement with said first mentioned means.

2. In a machine for assembling wheels in partially assembled condition where the spokes engage a metallic rim and are in angular relation to each other, the combination with a member engageable with the periphery of the rim to hold the same circular and to size, of a member for holding the rim in engagement with said first mentioned member, and means for angularly moving the spokes relative to the rim and to their permanent positions while the rim is in engagement with said first mentioned member.

3. In a machine for assembling wheels having a channel-shaped rim and spokes seating upon the rim, the combination of cooperating members engageable with the flanges of the rim to hold the rim circular and to size, and means for forcing the spokes into seating engagement with the rim and to their permanent positions while the rim is in engagement with said cooperating members.

4. In a machine for assembling wheels having a sheet metal channel-shaped rim with seats at the outer edges of the flanges thereof, the combination with means engageable with the seats to hold the rim circular and to size, of means engageable with the sides of the flanges to hold the flanges in their correct relative positions, and means for forcing the spokes into firm engagement 120 with the base of the rim and to their permanent positions while the rim is in engagement with said means.

5. In a machine for assembling wheels having wooden spokes and a sheet metal 130

channel-shaped rim with flared seats at the outer edges of its flanges, the combination with a ring engageable with a flange, of a ring having flared portions for engaging the 5 seats upon the flanges to hold the rim circular and to size, a pressure plate movable into engagement with the opposite flange, and means engageable with the inner end

portions of the spokes to force the same into firm engagement with the base of the rim 10 and to their permanent positions while the rim is in engagement with said rings and pressure plate.

In testimony whereof I affix my signature.

WILLIAM N. BOOTH.
